US00D558501S

(12) **United States Design Patent** (10) Patent No.: **US D558,501 S**
(45) Date of Patent: **** Jan. 1, 2008**

(54) **MEDIA STORAGE PAGE AND TWO-DISC HUB**

(75) Inventors: **Kevin Kirtz**, Massillon, OH (US);
Jesse D. Wells, Canton, OH (US)

(73) Assignee: **Nexpak Corporation**, Duluth, GA (US)

(**) Term: **14 Years**

(21) Appl. No.: **29/244,188**

(22) Filed: **Dec. 6, 2005**

Related U.S. Application Data

(63) Continuation-in-part of application No. 29/239,776, filed on Oct. 4, 2005.

(51) **LOC (8) Cl.** **06-02**

(52) **U.S. Cl.** **D6/626**

(58) **Field of Classification Search** D6/407, D6/450, 626-635; D9/433, 422, 418, 428, D9/522, 523, 544, 663; D3/303, 294, 218; D14/137, 479, 478, 474; 206/751, 755, 457, 206/312, 311, 310, 309, 308.2, 308.1, 307, 206/303, 232, 579, 493, 472; 720/719, 655, 720/728, 734; 211/40; 53/445, 462

(57) **CLAIM**

The ornamental design for the two-disc media hub, as shown and described.

DESCRIPTION

FIG. 1 is a perspective view of the two-disc media hub showing our new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side view thereof; and,

FIG. 7 is a right side view thereof.

The broken lines are included for the purpose of illustrating environment and form no part of the claimed design.
